CLAIM

The ornamental design for a body shape of a handset, as shown and described.

DESCRIPTION

FIG. 1 is a front view of a body shape of a handset showing my new design;

FIG. 2 is a rear view thereof;

FIG. 3 is a left side view thereof;

FIG. 4 is a right side view thereof;

FIG. 5 is a front perspective view thereof; and,

FIG. 6 is a rear perspective view thereof.

The broken line showing of various features of the handset is for illustrative purposes only and forms no part of the claimed design.
